UNITED STATES PATENT OFFICE.

DRURY E. STEVENS, OF PLEASANT HILL, LOUISIANA.

HAND CANCELING DEVICE.

1,109,480.

Specification of Letters Patent. Patented Sept. 1, 1914.

Application filed June 13, 1914. Serial No. 844,909.

To all whom it may concern:

Be it known that I, DRURY EDMOND STEVENS, a citizen of the United States, residing at Pleasant Hill, in the parish of 5 Sabine and State of Louisiana, have invented certain new and useful Improvements in Hand Canceling Devices, of which the following is a specification.

This invention comprehends certain new 10 and useful improvements in hand canceling devices and has for its primary object to provide a device of this character which will be of extremely simple construction and operation and formed in such manner that 15 the handle may be held at various angles without interfering with proper operation of the device.

Another object of the invention is to provide a device of this character which will be 20 formed in such manner that the parts may be readily assembled or taken apart for the purpose of repairing or replacing worn or broken parts, thereby eliminating the necessity of replacing the complete device should 25 one of the parts become worn or broken.

Another object of the invention is to provide a hand canceling device which will be 30 of such form that the head within which the stem is mounted will be free to swing for a limited distance in either direction upon the ball mounted on the lower end of the stem secured in the handle and having a cushion block mounted thereon and spaced slightly 35 above the head, thereby making it possible to properly stamp or cancel each piece of mail matter without holding the handle of the device in a vertical or perpendicular position.

This invention has for a still further object 40 to generally improve and simplify the construction and operation of devices of this character and increase the efficiency thereof without materially increasing the cost of the same.

With these and other objects in view as 45 will become more apparent as the description proceeds, the invention consists in certain novel features of construction, combination and arrangement of parts as will 50 be hereinafter more fully described and claimed.

For a complete understanding of my invention, reference is to be had to the follow-

ing description and accompanying drawings, in which—

55

Figure 1 is an elevation of the complete device assembled for use, Fig. 2 is a longitudinal section through the same, the upper portion of the handle being broken away, Fig. 3 is a detail transverse section on the line 3—3 of Fig. 2, looking in the direction indicated by the arrow, Fig. 4 is a detail sectional view on the line 4—4 of Fig. 2, and Fig. 5 is a detail elevation of the sectional head with the sections slightly spaced from 60 one another.

Referring in detail to the drawings by numerals, 1 designates the handle having an inwardly directed socket 2 formed in its lower end within which is snugly engaged a 70 stem 3 having radially directed wings 4 for engagement in outwardly directed slots or radially directed slots 5 communicating at their inner ends with a central aperture 6 of the cushion ring 7 formed of rubber or 75 other suitable material and mounted upon said stem 3 slightly above the upper end of the head encircling ring 8 and head sections 9.

It will be understood that the head sections 9 are inclosed in the head encircling ring 8 and said sections are provided with registering and co-acting semi-spherical recesses 10 in their upper faces to receive the ball 11 mounted upon the free end of the 85 stem 3. It will be understood also that the head sections 9 have curved outer faces, while their inner edges 12 are inclined to make it possible to readily force the head sections 9 into proper position within the 90 head encircling ring 8 and remove said head sections from said ring 8, as desired. Further, by forming the head sections 9 in this manner, they will be snugly engaged against the inner wall of the ring 8, and the 95 ball 11 on account of being engaged against the walls of both semi-spherical recesses 10, will prevent independent movement of the separate head sections 9 after said head sections have been forced to position within the 100 ring 8.

Positioned in the lower end of the ring 8 and engaged against the lower serrated faces 13 of the head sections 9 is the stamp 14, preferably formed of rubber and having a 105 roughened working lower face 15 which, it

will be understood, is positioned outwardly of the lower end of the ring 8 in order that said working face 15 may be engaged with stamps or other articles of mail matter to 5 cancel or mark the same without danger of the edge of the ring 8 engaging said stamp or mail matter.

From the foregoing, it will be readily apparent that as there is a space between the 10 upper end of the ring 8 and head sections 9, and the lower end or face of the cushion ring 7, which preferably has its upper end or face engaged against the lower end of the handle 1, said head sections 9, ring 8 and 15 stem 14 may be readily swung at various angles to the handle 1 and the device operated to plainly mark all stamps and pieces of mail matter with which the stamp 14 is engaged, regardless of the position in which 20 said handle is inclined. It will further be readily seen that the cushion ring 7 serves to relieve the handle 1 of the shocks incident to the stamp 14 being forced into engagement with the mail matter and stamps 25 to be marked and also lends a resilient action to the device and does not tend to return the head sections 9, ring 8 and stamp 14 to normal position as suddenly as would be the case should a spring be employed 30 instead of the cushion block 7. Further, should a spring be employed, it would be impossible to leave a space between the stamp and the head sections 9 and head encircling ring 8 and thereby permit the free 35 movement of these parts which is essential to proper and efficient operation of the device.

While I have shown and described the preferred embodiment of my invention, it 40 will be understood that minor changes in the details of construction, combination and arrangement of parts may be made without departing from the spirit and scope of the invention as claimed, or sacrificing any of 45 the advantages thereof.

What is claimed is:—

1. A device of the class described comprising head sections having registering recesses, a head encircling ring engaged 50 around said sections to retain the same in proper position, a stem having an enlarged portion formed on one end and engaged in said registering recesses, a handle for said stem, a cushion member mounted upon said 55 stem above said head sections and adapted for engagement with the latter, and a stamp mounted in the ring beneath the head sections.

2. A device of the class described comprising head sections having registering recesses opening upon one face, a stem, a ball 60

formed on one end of said stem and engaged in said registering recesses, a handle mounted upon said stem, a cushioning member mounted upon said stem between said handle and said head sections and adapted for engagement with the latter, means for retaining said head sections in engagement with one another, and a stamp mounted in the last mentioned means beneath said head 65 sections.

3. A device of the class described comprising head sections having registering semi-spherical recesses in their upper ends, a stem, a ball formed on one end of said 70 stem and engaged in the registering semi-spherical recesses of the head sections, a ring for securing said head sections in engagement with one another, a stamp member carried by said ring and projecting from 75 the same, said stamp member being engaged against one face of the head sections, a handle mounted on said stem, and a cushion ring mounted on said stem between the handle and the head sections and slightly 80 spaced from the latter.

4. A device of the class described comprising head sections having inclined adjacent faces, said head sections being provided with semi-spherical registering recesses in their upper portions, a ring engaged around said head sections, a stamp engaged in said ring and against the under faces of said head sections, said under faces of the head sections being roughened to prevent rotation of the stamp, a stem, a ball mounted upon said stem and engaged in the 90 registering recesses of the head sections, a handle for said stem, and a cushion member mounted upon said stem and positioned between the head sections and the handle for 95 engagement with the former during operation of the device.

5. A device of the class described comprising a head having a substantially spherical recess formed therein and opening upon one face, a stem having a substantially spherical end engaged in said recess, radially directed projections formed on said 100 stem, a cushion ring mounted on said stem, said projections being engaged in said ring to prevent rotation of the latter upon said stem, a handle for said stem outwardly of the cushion ring, a head encircling ring, and a stamp member in said ring beneath said 105 head.

In testimony whereof I affix my signature in presence of two witnesses.

DRURY E. STEVENS.
